UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

MACHINE FOR BORING SPHERICAL SOCKETS.

Application filed March 11, 1924. Serial No. 698,432.

My invention relates to mechanism designed for boring out a spherical socket in the bell end of a cast pipe and has for its object to provide mechanism by which this work can be done with speed and accuracy. The nature of my improvements will be best understood as described in connection with the drawings in which they are illustrated and in which

10 Figure 1 is a sectional elevation of a bell mouth pipe and of a portion of the supporting mechanism also shown in section with a boring apparatus shown in side elevation and in place in the pipe.

15 Figure 2 is an end elevation showing the bell end of the pipe, the mechanism for supporting the pipe and the boring apparatus in position.

Figure 3 is a sectional view on the line 20 3—3 of Fig. 1.

Figure 4, a sectional view on the broken line 4—4 of Fig. 3.

Figure 5, a view on the line 5—5 of Fig. 3, and

25 Figure 6 is a view in part similar to Fig. 1, but showing the boring tools in a different position and the adjustable handle for shifting the tools.

A, A, indicate the base beams on which 30 the pipe supporting apparatus rests. These beams are formed with T shaped slots, as indicated at A¹, and support the blocks B, B, which are adjustable along the beams A, and are secured in desired positions by the bolts 35 indicated at b, b, etc. The blocks B are alternately flanged, as indicated at B¹, B¹, and support the cross bolsters indicated at C, C, which are secured to them by the bolts indicated at c, c, etc., and which cross bolsters

40 are formed with T-shaped slots, as indicated at C¹, C¹, and support in turn the pipe seats indicated at D, D, which are adjustably secured in place by means of bolts indicated at d, d. In order that the pipes may be firmly 45 seated on these pipe seats, I provide in the lower central portion of each seat, an adjustable portion indicated at D¹ which is adjusted and held in position by means of a bolt D², as best shown in Fig. 1.

50 Also adjustably secured on the cross bolsters C are the heads indicated at E, E, which are held in place in adjustable position by means of the bolts e, e, etc. and through which extend the bolts F¹ with ad-

justing nuts indicated at F², which bolts 55 are attached to the ends of a gripping chain, indicated at F.

G is the pipe having a bell end G¹ in which a spherical socket is to be formed and which pipe is secured on the pipe rests D by means 60 of the chains F, the adjustable parts in the supporting mechanism described being intended to adapt this supporting mechanism for pipes of different size and also to make it practicable to adjust the position of a 65 pipe into proper relationship with the driven head indicated at H, to which head is secured the shaft H¹ extending through the pipe and supporting at its end, which extends into the bell of the pipe, the head indicated 70 at H². The shaft H¹ is supported in the pipe by the bearings I, I, which are provided with set screws, as indicated at I¹, for properly adjusting them in the pipe and securing them to the pipe. The shaft H¹ is held 75 against a lateral movement in its bearings, partly by the rings I², I², (see right hand side of Fig. 1) which is secured to the shaft by set screws i² and which abut against the ends of the right hand bearing I, and I make still 80 further provision for holding the shaft in fixed position in its bearings by providing a shouler h² which abuts against a washer h³ at the end of the left hand bearing I, while against the right hand end of this bearing 85 I place a ring I⁵ which abuts against a series of adjusting screws i⁴ in a ring I³ which is secured to the shaft H¹ by the set screws indicated at i⁵.

In the center of the head H² formed at the 90 end of the shaft H¹, I secure a bearing pin J having annular rings J¹ J¹ screwing upon its ends and preferably having the cap as indicated at J² for closing its end. The head H² is forked, as best shown in Fig. 3, and, of 95 course, its outer end is secured to the plate indicated at K which supports the bearing pin indicated at K¹, upon which bearing pin is secured the gear wheel K² having the crank handle K³ attached to it. This gear wheel is 100 in engagement with the gear wheel K⁴ secured to a shaft K⁵ having attached to its inner end a worm K⁶ which in turn engages the worm wheel K⁷, having formed on or attached to it the worm indicated at K⁸ 105 which in turn engages a worm wheel segment L¹ attached to a rotating head L, supported on the bearing J and having positively ex-

tending arms L^3 , L^3 . Upon these arms are adjustably secured the tool holding heads M , M , carrying tools indicated at M^1 , and secured in adjusted positions by means of the bolts indicated at M^2 secured to one of the arms L^3 . The upper one, as shown in Fig. 4, has the flanged plate M^3 carrying an adjustable abutting screw M^4 in alignment with a lug M^5 on the upper tool holding head M , and by means of which a very nice adjustment of the tool can be effected. N , N , are sleeves secured to the head L and N^1 , N^1 , internally threaded sleeves secured to the tool holding heads M , M , N^2 , N^2 , are threaded rods journaled in the sleeves N , N , screwing in the threaded sleeves N^1 , N^1 and connected together at their inner ends by a universal joint, indicated at N^3 .

When it is desired to bore out a spherical socket in the pipe end G^1 , the pipe is secured in its described supporting mechanism and brought to proper alignment with the driving head H ; at the same time the shaft H^1 carrying its bearings I , I , is inserted into the pipe, nicely adjusted so that the bearing pin J will extend through the center of the spherical socket to be formed in the pipe and the bearings I , I , are then firmly secured in and to the pipe by means of the set screws I^1 and the shaft H is, of course, attached to the driving head H . The tools M^1 , M^1 , are properly adjusted to cut the bell in the spherical form desired and the shaft H is set in action and the proper contact of the tools effected by the rotation of the crank handle K^3 which, through the mechanism described,

revolves the tools around the bearing pin J with the result that a spherical bell is formed in the end of the pipe.

It is desirable that at the line G^1 , where the spherical end of the pipe merges into the cylindrical portion, a smooth junction should be formed and to effect this when the head H^2 is swung to the position indicated in Fig. 6, the tool, in what is there the upper head M , is removed and the handle N^4 is attached to the end of the threaded rod N^2 and turned so that the remaining tool M^1 in the lower head M will smooth off the annular junction between the sphere and the cylinder, as indicated in Fig. 6.

Having now described my invention, what I claim as new and desire to secure by Letters Patent, is:

Mechanism for boring a spherical socket in a pipe end comprising in combination a rotatable shaft having a head at its end, a tool carrier pivoted on said head so as to be adjustable in a plane parallel to the shaft but not otherwise movable with reference to the shaft, said tool carrier having two oppositely extending tool supporting arms, tool holders adjustably supported on the arms of the carrier, means for simultaneously adjusting the tool holders, and means for angularly adjusting the tool carrier on the head consisting of a worm wheel segment secured to the tool carrier and a worm and gear train attached to the head and including an actuating gear journaled at the end of the head for angularly adjusting the tool carrier.

JOHN H. UHRIG.
